UNITED STATES PATENT OFFICE.

TRYGVE A. HALL, OF POUGHKEEPSIE, NEW YORK.

SCLEROSCOPE.

Application filed September 18, 1923. Serial No. 663,421.

This invention relates to portable scleroscopes and hardness testers of the class in which a plunger released striker is adapted to travel in a graduated tube, and is more particularly an improvement over my Patent #1,446,620 for a scleroscope, dated February 27, 1923.

In the mentioned patent, I disclose the construction of the graduated tube and a striker adapted to drop through the same with means to hold the striker in raised position and also to release the same, with further means upon the striker and in the tube to catch and hold the striker upon rebounding from a test object.

The main object of the present invention is to introduce improved means to perform these functions, and incidentally, to improve the construction of the scleroscope as a whole.

Referring to the drawing forming part of this application:—

Fig. 1 is a vertical side section of an apparatus made according to my invention with all parts in initial operative position.

Fig. 2 is a similar view with the striker released and the lower part of the apparatus omitted.

Fig. 3 is a vertical section of the lower extremity of the scleroscope of Fig. 1 with the striker at the bottom with pawls released.

Fig. 4 is an intermediate vertical section of the same instrument with the striker at rest in attained rebound position.

Fig. 5 is a front view of the same part of the instrument.

Fig. 6 is a cross section of the scleroscope immediately above Fig. 5.

Throughout the views in the drawings the same reference numerals indicate the same parts.

My new scleroscope consists of a main tube 1 screwed to a base 2, and having the interior chamber 3 in which a striker 4 is adapted to move vertically. Above the striker a wide slot 23 is provided in the tube to permit easy access to the interior when assembling the instrument, and in this slot 50 is mounted a swinging member or trigger 21 adapted to rotate about a shaft 22. This pendant member is provided at one side of the center with a spring 24 which contacts with the tube 1 to give the upper extremity 55 a decided tendency to occupy a central position in chamber 3. Below the spring

24, the part 23 is formed into a hook 13 adapted to engage the head 14 with which the striker is provided, serving to retain the latter in raised position.

A cap 27 is screwed into the upper extremity of tube 1, and contains a compression spring 28, while a plunger 29 which surmounts the instrument has a reduced portion 30 resting on the spring. Furthermore, the plunger is provided with a narrow neck 44 which passes through the cap and terminates below in a head 26 adapted to contact with one side of part 25. Thus, the immediate effect of depressing the plunger 70 would be to swing member 21 into the position of Fig. 2, releasing the striker.

However, the construction of the striker comprises a body portion surmounted by a head, as noted, a reduced portion 20 having a flange 17, and an annular rib 16 on the body, the flange and rib centering the striker in the tube by slight contact with its interior. The lower part of the striker is furnished with a very hard steel head or hammer 18, whose shank 19 is driven hard into part 20. In order to prevent the striker from turning in movement, a slot 36 is provided in the side of the tube 1 and a projecting pin 35 secured in the striker extending slightly into the slot, while a transverse shaft 15 forms an upper limit for the striker, a shoulder 45 adapting it to contact with the body 4 and cause the head 14 to register properly with the trigger hook 13.

But the tube 1 is further provided with a rack 37 in slot 36, whose use will immediately appear. The striker is provided with a slot 5 in which are located an escapement hook 6—8 and a double pawl 9—10. The first hook is adapted by the hook 8 to engage either tip 9 or 10 of the pawl, but owing to the limited movement possible to the hook 8 about the center 7, the tip 10 will never clear it and will therefore limit outward swing of the pawl. The pawl is provided with a leaf spring 11 which is under tension against leg 6 of the escapement hook, and causes the pawl to tend to spring out into the tube slot 36. The trigger 21, on the other hand, terminates at its lower extremity in a finger 12 so related in size and position to the pawl that whenever the striker is caused to approach the trigger and abut the shaft 15, the finger will invariably push the pawl into the striker and permit hook 8 to rise and lock tip 9.

It is to be noted that while hook 8 is heavy in construction, the tension of spring 11 on the inside of leg 6 will raise hook 8 when tip 9 is within it because the spring is drawn up above the center 7.

When the striker is caused to drop by depressing plunger 29, as has been described, the striker will drop through the tube until the hammer 18 passes into aperture 38 in base 2 and strikes a test surface upon which the scleroscope is standing at the time, and as it strikes the momentum still retained by the hook 8 will cause the latter to drop, releasing tip 9 of the pawl as in Fig. 3. Then rebounding, the striker will rise to assume a position like that of Figs. 4 and 5, while tip 9 will contact with the rack 37 on the way up, but will instantly engage the latter when the striker comes to a stop, preventing its descent. The distance of the rebound is, of course, a direct index of the hardness of any object tested, and in order to make possible the accurate reading of attained striker positions, a marked portion 48 is provided to the striker and primarily, a slot 43 in tube 1 through which to view the mark. The tube is flattened exteriorly adjacent the slot as at 47, and a pair of graduated strips 42—42 secured on either side of the slot, a glass 41 being laid outside the strips to protect the same and close the slot.

However, in order to completely assemble the instrument, an outer tube 32 is fitted over tube 1, and at the bottom a finishing ring 34 secured, while a capping tube 31 is fitted over the upper portion of tube 1 and cap 27, the plunger passing through the capping tube, and a second finishing ring or collar 33 joining the tubes to finish the whole.

The base of the instrument is provided with a pair of transverse bottom grooves to facilitate accurate centering of the instrument upon round shafts and like objects.

It might be mentioned, finally, in regard to the striker, that if the latter actually filled the bore 3 of tube 1, it would not drop very rapidly because of air resistance, and to remedy this condition, a pair of opposite corresponding clearance slots 40—40 in the body 4 and like 46 in flange 17 have been cut, permitting a free drop.

If the base of the instrument is now directly placed on a surface which is to be tested and then the plunger pressed without disturbing the instrument, the striker will drop and instantly rebound stopping at some mark on the index strips. The number on the strips indicated by striker mark 48 will be the hardness number. Before leaving this point it may be well to note that when the striker pawl has been freed by a drop, the pawl spring is swung down slightly so that its lower extremity has practically passed the center 7, this extremity will

actually push down hook 8, thus reversing its normal action.

Returning to the operation of the device, it is but necessary to invert the apparatus in the hand in order to cause the striker to ascend to initial starting position. When the scleroscope is inverted, the striker will drop toward trigger 21, while finger 12 of the same will depress the pawl till hook 8 drops outside the pawl, locking the latter. The trigger is, of course, momentarily rocked out of position by the head of the striker, but only resumes its usual position when the striker has come to rest against tube stop 15, and hook 13 has caught striker head 14. Returning the instrument to normal position, it is again ready for a test, and any number of tests may thus be made.

Having now fully described my invention, I claim—

1. A scleroscope comprising a tube having a base and a pair of longitudinal slots, a rack in one of said slots and a graduated indicator beside the second slot, a striker movable in said tube having a retaining means comprising a head upon its upper portion and a contact hammer upon its lower portion, intermediately, a double pawl on said striker provided with a spring and adapted to engage said rack, a hook on said striker contacting with said pawl spring and adapted to engage said pawl, and means on said tube to engage and release said striker head.

2. A portable scleroscope comprising a tube having interiorly a stationary rack, a movable striker adapted when in projected position to travel in said tube having a pendant pawl adapted to engage said rack, a pivot in said striker and an escapement hook mounted on said pivot in said striker having a relatively long, light leg at one side of said pivot and opposite the same a relatively heavy short leg adapted to engage said pawl when in retracted position, a spring secured to said pawl adapted to rest against said long leg tending to raise said short leg and project said pawl outward and means in said tube to engage or release said striker comprising a catch hook and a plunger adapted to displace said catch hook.

3. A scleroscope comprising a tube provided interiorly with a fulcrum pin, a pendant hook mounted on said pin having a projection above the fulcrum pin, a second projection below the same, a spring on said hook in contact with said tube, a striker having a contact hammer beneath the same, and surmounting the same a head adapted to be engaged by said pendant hook, a rack located in the side of said tube, a pendant pawl pivoted in the side of said striker adapted to engage said rack when in released position and provided with a spring engaging a part of said striker to project

- said pawl outward, a stop for said striker in said tube, a pivoted hook in said striker adapted to engage said pawl when in withdrawn position, said pendant pawl being 5 adapted to contact with the lower portion of said pendant hook to be retracted thereby, and a depressible plunger in said tube adapted to engage the upper portion of said pendant hook to swing the same.
- 10 4. An invertible scleroscope comprising a tube having in the extremity thereof a projecting plunger and a hook pivoted within the tube in contact with said plunger, a spring upon said hook in contact with the 15 wall of said tube, a striker adapted to reciprocate in said tube and adapted to be engaged by said hook, a rack in said tube, a pendant pawl pivoted in the body of said striker adapted when in released position to 20 engage said rack in said tube, a projection upon said hook adapted to swing said pawl inward into inoperative position upon movement of said striker toward said hook, a fulcrum pin in said striker body and an 25 escapement hook mounted on said fulcrum pin in said striker adapted to engage said pawl when in normal inner depressed position, and a spring on said pawl adapted to be tensed against said escapement hook 30 above the fulcrum thereof tending to raise the same when said pawl is in withdrawn position, and adapted when said pawl is in projected position to contact with said hook below said fulcrum whereby to depress said 35 hook.
5. A scleroscope comprising a tube, a hook pivotally mounted in said tube having a projection on the same, a plunger adapted when in depressed position to swing said hook, a movable striker in said tube, a limit stop therefor secured in said tube, a head on said striker adapted to be engaged by said hook, a pendant pawl pivoted in said striker, a projection spring secured upon 40 one side of said pawl and an outer short pawl tip secured upon the other side of the pawl and intermediately an inner long tip, an escapement hook provided with a pair of different extremities and also pivotally 45 mounted in said striker adapted at one extremity to engage either of said pawl tips and within the other extremity adapted to engage the interior of said striker and partially envelop said projection spring, said 50 long pawl tip being so relatively proportioned that only the short tip may escape and project against the inside of aforesaid tube, said long tip thereby providing a limit for said pawl together with said escapement hook, and a second projection on aforesaid pendant hook adapted to engage and depress said pawl within the limits of 55 said striker.
6. In a scleroscope, a striker clutch and release device comprising a tube of the char- 60 acter described, a trigger hook movably mounted in said tube, an upper and a lower projection on said hook, an intermediate hook and a spring secured thereto and projecting therefrom to the wall of said tube, a 65 plunger adapted to contact with said hook and adapted upon depression thereof to displace said hook, a striker body, and a pendant pawl mounted in said body, a spring on said pawl and a pair of spaced points on 70 said pawl, an escapement hook pivotally mounted in said striker body, a long arm and an oppositely disposed shorter arm terminating in a hook adapted when in retracted position to engage the outermost point of 75 said pawl and adapted to engage the inner second point when in projected position to limit the projection of said pawl, said pawl spring in said retracted pawl position being 80 adapted to be tensed against said long hook arm above the pivot mounting of said hook and thereby raise the shorter hook arm and thus lock said pawl in retracted position, said spring in projected pawl position being 85 adapted to contact with another portion of 90 said escapement hook to depress said hook and thereby prevent return of said pawl, said pawl being adapted to contact with one of the projections of aforesaid trigger to retract said pawl and lock said escapement 95 hook.
7. A scleroscope comprising a tube, a rack in said tube and a striker adapted to slide in said tube, a pair of spaced pivots in said striker, a pawl mounted on one of said pivots and an escapement hook mounted on the other, a spring on said pawl adapted to contact with said escapement hook, a straight arm and a hooked arm on said escapement hook, said hooked arm being adapted to engage said pawl when the latter is in withdrawn position, and said pawl being adapted to engage said rack when in projected position, and means in said tube adapted to contact with said pawl to retract the same and 100 to permit said hooked arm to engage and lock said pawl.
8. In a scleroscope having a tube provided with a rack therein, a striker comprising a striker body, a pair of spaced pivots, a pawl mounted on one of said pivots, an arched escapement hook mounted on the other pivot and partly enveloping said pawl, a weighted arm on said escapement hook and a hook on 105 said arm adapted to engage said pawl when the same is in withdrawn position, means to project said pawl to permit the pawl to engage said rack, means in said striker to move said hook into engagement with said pawl in the retracted position of the latter and means 110 to depress said pawl.
9. In a scleroscope striker, a striker body, a pair of spaced and parallel pivots, a pawl mounted on one of said pivots and an escapement hook mounted on the other and in 115 120 125 130

the same plane with said pawl, means to project said pawl, means to lock and retain said pawl in retracted position comprising a hook upon said escapement hook, and 5 means to retain said hook in raised position in engagement with said pawl.

10. In a scleroscope, a striker mechanism comprising a striker body, pivots in said body, a hook mounted on one pivot and a 10 pawl mounted on another pivot, a main tip on said pawl adapted to be engaged by said hook and relatively of a length to be permanently captive within the confines of said hook, a second relatively shorter tip on said 15 pawl adapted to be engaged by said hook when the pawl is in retracted position but adapted to project beyond said hook when in projected position, and means to project said pawl from said hook comprising a 20 spring between said pawl and said hook.

11. In a scleroscope, a striker mechanism comprising a striker body, a pawl pivoted in said body, a hook mounted in said body and adapted to envelope said pawl and to engage 25 said pawl when in retracted position, and

means to project said pawl and also to move said hook into engagement with said pawl comprising a spring secured upon said pawl and adapted to slide upon the inside of said hook.

12. In a scleroscope, a striker comprising a striker body, a pair of pivots in the same, a pawl mounted on one of said pivots and an escapement hook mounted on the other pivot, means to project said pawl beyond said hook, 35 a relatively light arm on said escapement hook and a weighted arm on said escapement hook, a hook on said weighted arm, said hook being adapted to engage said pawl when the latter is in retracted position, and 40 said weighted arm being adapted to withdraw said hook from said pawl by virtue of its momentum upon movement of said striker, and means to retain said hook normally on engagement with said pawl when 45 in withdrawn position.

In testimony whereof I have affixed my signature.

TRYGVE A. HALL.
